Inventor.

UNITED STATES PATENT OFFICE.

ISIDOR KITSEE, OF PHILADELPHIA, PENNSYLVANIA, ASSIGNOR TO CHARLES E. WILSON, OF SAME PLACE.

SPACE TELEGRAPHY.

SPECIFICATION forming part of Letters Patent No. 651,362, dated June 12, 1900.

Application filed May 20, 1899. Serial No. 717,615. (No model.)

To all whom it may concern:

Be it known that I, ISIDOR KITSEE, of the city and county of Philadelphia, State of Pennsylvania, have invented certain new and useful Improvements in Wireless or Space Telegraphy, of which the following is a specification.

My invention relates to an improvement in wireless or space telegraphy.

The object of my invention is to produce a buoy capable of transmitting electrical impulses of prearranged duration and intervals. Buoys, as is well known, are placed at locations which are considered dangerous for sea-going vessels, and it has been the aim to provide such buoys with devices with the aid of which their presence should be known to vessels passing near by, so that they may be able to avoid the danger. The knowledge of the location of these buoys is of the greatest importance for vessels in foggy or stormy weather, and so far no device is in existence capable of warning the passing vessels of their presence. To produce such a device is the aim of my invention.

Referring to the drawings, Figure 1 is a side elevation of the buoy; Fig. 2, a diagrammatic view showing the electrical connection of my device partially inclosed in and partially out of the buoy.

30 A is the buoy proper; B, the mast secured to the buoy, having secured thereto the sphere b.

C is a tube secured to the bottom of the buoy, provided with the anchor-cable eye c.

35 D is a carbon plate; E, a zinc plate. Connected to the carbon plate D through the wire 5 is one terminal of the electrolytic interrupter consisting of the platinum wire II, provided with the insulation I and the conducting-tube C'. The other terminal of the

40 interrupter is connected through the wire 6 with the brush j', which brush is in electrical connection with the drum J, the periphery of which consists of metallic points alternating 45 with insulated spaces. On this drum rests the brush j, connected through wire 3 with the primary P of an inductorium. The other terminal of the primary is connected through wire 4 with the zinc plate E. In proximity 50 to the primary P is the secondary S, one terminal of which is connected through wire 2

with the ground or water G, the other terminal through wire 1 with the aerial conductor b. The plates D E fulfil the office of electrodes of a voltaic cell, and the salt water of 55 the ocean or sea fulfils the office of the electrolyte of such cell. If a carbon plate and a zinc plate are immersed in sea-water, the voltage developed is about one and five-tenths, and each square inch exposed will give, if the 60 two plates are not too far apart, about three-eighths of one ampere, and as the water of the sea is always in motion polarization will be obviated. The working of the electrolytic interrupter is to-day so well known that it 65 does not need further explanation.

The plates D E are secured to the buoy in such manner that the greatest part of these plates is exposed to the waves of the ocean, and the electrolytic interrupter is also to its 70 greatest part immersed in the water, and, with the exception of the aerial conductor, all other parts are inclosed in the buoy. Through the immersion of the zinc and carbon plates an electric current is generated. This current passes through the primary coil, wire 3, brush j, metallic contact-point of the drum J, brush j', wire 6, electrode H of the electrolytic interrupter, through the water to electrode C', and through wire 5 and plate D and 75 water as an electrolyte back to the plate E.

The drum J may be actuated by any of the well-known means, either mechanical, through a clockwork, or electrical, with the aid of a motor. On the periphery of the drum are, as 85 stated before, conducting contact-points. They are grouped in such manner as to represent the prearranged number which should correspond to the number of the buoy placed on the chart. It is understood that the contact-points are in electrical connection with the conducting-drum.

The working of the device is as follows: The generated straight current is made an interrupted one with the aid of the electrolytic interrupter and will therefore induce 95 impulses in the secondary. These impulses, if of high enough potential, will, with the aid of the aerial conductor, be transmitted to objects, such as vessels, and translated into 100 sound or record if these vessels are provided with a suitable receiver for these current im-

pulses or waves; but these interrupted or recurring impulses can only flow to the primary if both of the brushes j, j' are in electrical contact with each other, and as this electrical contact is only possible when the brush j strikes one of the contact-points on the periphery of the drum it is obvious that the transmitted electric impulses will be in accordance with the grouping of these contact-points, and as these contact-points represent the number of the buoy it is obvious that the transmitted electric impulses when translated into sound, glow, or record will in their grouping also represent the number of the buoy from which the impulses are transmitted.

I have in the drawings illustrated the device as being provided with one voltaic couple immersed in the sea-water to generate the necessary current; but if it is found that the potential of the current is too low for practical purposes other voltaic cells, primary or secondary, may be substituted for the couple, as described. I have also illustrated in the drawings an electrolytic interrupter; but any other of the well-known mechanical or electromagnetic devices may be substituted. So, for instance, can the terminals of the wires 5 or 6, now connected to the electrolytic interrupter, be connected to brushes of a mechanical interrupter revolving on the same shaft as the drum J revolves.

Having now described my invention, what I claim as new, and desire to secure by Letters Patent, is—

35 1. In wireless or space telegraphy an automatic sending station consisting of a buoy provided with means for supplying the cur-

rent, means for interrupting the current, means for automatically sending prearranged signals and means for transforming the currents into currents of the necessary high intensity.

2. In wireless or space telegraphy, an automatic sending-station comprising a buoy, a source of electric energy, means electrically connected with said source for making and breaking the circuit at prearranged intervals, a primary coil and an interrupter in circuit with said source of energy and said circuit making and breaking means, an aerial conductor, and a secondary coil in circuit with said conductor.

3. In wireless or space telegraphy, an automatic sending-station comprising a buoy, a voltaic pile or couple adapted to be immersed in the sea-water, means electrically connected with said pile or couple for making and breaking the circuit at prearranged intervals, a primary coil and an interrupter in circuit with said pile or couple and said circuit making and breaking means, an aerial conductor, and a secondary coil in circuit with said conductor.

4. In wireless or space telegraphy, an automatic sending-station comprising a buoy, a source of electric energy, and means for automatically transmitting prearranged signals at prearranged intervals.

In testimony whereof I sign my name in the presence of two subscribing witnesses.

ISIDOR KITSEE.
